UNITED STATES PATENT OFFICE.

MERRITT W. GRISWOLD, OF HIGHWOOD, NEW JERSEY.

SASH-LOCK.

No. 926,482.

Specification of Letters Patent.

Patented June 29, 1909.

Application filed March 5, 1908. Serial No. 419,245.

To all whom it may concern:

Be it known that I, MERRITT W. GRISWOLD, a citizen of the United States, residing at Highwood, in the county of Bergen and 5 State of New Jersey, have invented a new and useful Sash-Lock, of which the following is a specification.

My invention relates to improvements in window sash-locks but more especially to 10 those in railroad cars for automatically lowering the windows part way down by the shaking of the cars and there securely locking them at a point where the incoming dust, cinders, etc., will not strike directly into the 15 face and eyes of passengers while the train is moving. I attain this object by the mechanism illustrated in the accompanying drawings in which:

Figure I. is a perspective view of a car 20 window showing a portion of the sash and window frame partly cut away. Fig. II is a side view of the lock case (2) showing the protruding end of the lock bolt (7). Fig. III. is a front view of the rack or bolt runway. Fig. IV. is a sectional view of Fig. III taken through its center. Fig. V. is a front view of a car window wherein the full lines show the sash high up at a time when the car is standing still and the dotted lines when 30 positively locked at a point part way down. Fig. VI. is a view of the lock with its front case cut away. Fig. VII. is a side view of Fig. VI.

Similar characters refer to similar parts 25 throughout the several views.

1— is the window sash, 2— is the lock case or shell, 3— the screws that secure the lock to the sash.

4— is a wide opening in the lock case 40 through which the bolt head has free play, 5— is the tail end of the bolt, 6— is the operating lug on the bolt, 7— is the engaging end of the locking bolt, 8— is an expanding spiral spring for keeping the bolt pushed 45 outward into action within the rack or bolt runway in the frame of the window, 9 and 9^a are respectively pin and ball-socket pivots for sustaining the operating lever, 10 is the arm of the operating lever, 11— is a dog on 50 the arm (10) engaging with the lug (6) for operating the bolt (7) by hand, 12— is a thumb piece on the arm (10) for operating the bolt, 13— is a thumb rest attached to the case (2), 14— is the window frame, 15— is 55 the window-sill, 16— is the sash-runway in

the frame of the window, 17— is the back part of the rack or bolt-runway, 18^a, 18^b, etc., are full width ratchet-teeth or lugs, 19— are serrations or teeth placed staggered with each other on each inner side-wall of the 60 rack with a space between the end or point of each tooth and the opposite side-wall sufficient to allow the bolt to freely pass through.

20— is a lug for locking the window when 65 closed all the way down, 21— is the glass in the sash.

The operation is as follows: By pressure upon the thumb piece (12) the bolt (7) is drawn back out of the action within the 70 rack or bolt-runway to allow the sash to be freely raised or lowered. If pressure on the thumb piece be removed at a point when the bolt is anywhere above the full ratchet tooth 75 (18^a) the bolt head (7) will be forced forward by the spring and rest upon and be held by one of the staggered teeth or serrations (19) in the upper part of the runway so long as in a state of rest, but after the car begins to move the resultant shaking and jarring will 80 cause the bolt to slowly slide along the inclined upper surface of the short tooth or lug toward the opposite wall of the rack or runway until the bolt (7) clears the point of the tooth or lug (19) on which it rested, and 85 allow the window to slide down by its own weight until the bolt rests on the next tooth or serration at this other side of the runway; here it is again stopped and held until the 90 vibration or shaking action, as above described, carries the bolt (7) along the incline of the tooth on that side and over against the opposite wall of the runway, again dropping the window as before described and so on 95 throughout the serpentine channel formed by the series of staggered serrations until the bolt rests upon the full size ratchet tooth (18^a) where it permanently locks. If desired to place the window farther down, all 100 that is required is to press up on the thumb piece (12) and disengage the bolt (7) from lug (18^a) and lower the window by hand to 18^b or 18^c, &c.

The opening 4 in the lock-case is sufficiently wider than the bolt 7 to allow the 105 required lateral play of the latter in following the staggered or serpentine path above described, and the lug 6 on the bolt 7 is of sufficiently less width than the space between 110 the side walls of the lock-case to permit such

lateral movement while maintaining engagement with the dog 11 on the operating lever 10.

In the modified form of the invention shown in Figs. VI and VII the bolt and operating lever are in a single piece suspended by a ball and socket joint at 9^a with freedom to oscillate in both directions as required.

I claim:

10 1. A rack, inwardly-projecting alternately-spaced serrations on the inner faces of the side walls of said rack, forming a serpentine channel therein, adapted to serve with a sash-lock having a laterally-swinging retractable bolt arranged automatically to engage and release said serrations successively and to traverse said channel.

20 2. A rack, ratchet teeth at the lower portion thereof, and inwardly-projecting, alternately-spaced serrations on the inner faces of the side walls of said rack at the upper portion thereof, forming a serpentine channel therein, adapted to serve with a sash-lock having a laterally-swinging retractable bolt

arranged automatically to engage and release 25 said serrations successively and traverse said channel, and to engage said ratchet teeth.

3. A sash-lock comprising a casing having an opening, a bolt projecting through such opening and arranged to swing laterally 30 therein between the side walls of said casing, and a spring exerting its force to hold said bolt yieldingly protruded through such opening, in combination with a rack, ratchet teeth on the lower portion thereof, and inwardly-projecting alternately-spaced serrations on the inner faces of the side walls of said rack at the upper portion of the latter, forming a serpentine channel therein, said bolt adapted automatically to engage and 40 release said serrations successively and traverse said channel by swinging laterally in said casing, and to engage said ratchet teeth.

MERRITT W. GRISWOLD.
